UNITED STATES PATENT OFFICE.

PHILIP F. LENHART, OF BROOKLYN, NEW YORK, ASSIGNOR OF SEVEN-EIGHTHS TO ATKINS STOVER, OF SAME PLACE.

COMMUTATOR-PATTERN.

SPECIFICATION forming part of Letters Patent No. 445,319, dated January 27, 1891.

Application filed June 17, 1890. Serial No. 355,711. (No model.)

To all whom it may concern:

Be it known that I, PHILIP F. LENHART, of Brooklyn, in the county of Kings and State of New York, have invented a certain new and useful Improvement in Patterns for Casting Commutators, of which the following is a specification.

My invention relates to an improvement in patterns for casting commutators, the object 10 being to provide a pattern by which these several radial sections of a commutator may be cast simultaneously and with accuracy, either with the insulating material between or a space for the reception of such material between them as 15 may be found expedient.

In the accompanying drawings, Figure 1 represents an end view of the pattern. Fig. 2 represents a view of the same in side elevation, and Fig. 3 represents a central longitudinal section.

The pattern comprises a cylindrical body portion with tapered ends provided with wings radiating from its surface and extending longitudinally thereof, the said wings corresponding to the layers of insulating material to be interposed between the several radial sections of the commutator.

In order to provide for the reception of the core, the pattern is provided at its opposite ends with core-prints, and for the purpose of uniting these several sections when cast, so that they may be successfully withdrawn from the mold, the pattern is provided with an annular ring at its upper and lower portions.

The particular construction of the pattern is as follows: A represents the cylindrical body portion of the pattern provided with tapering ends *a*, as shown. The angle of inclination of the tapered ends *a* is such as to afford a sliding bearing for the face of a cap-screw (not shown) of the ordinary and well-known construction for binding the several radial sections of the commutator together when completed. At the ends of the tapered portion *a* core-prints B are secured. From the periphery of the cylindrical portion A wings C radiate. The wings C may either be secured to the surface of the body portion A and form in the mold a series of slots for the reception of thin layers of insulating material, extending from said

slots into the wall of a core, the ends of which are intended to rest in the seats formed by the core-prints B when the pattern is withdrawn from the mold, or the said wings C may extend from points on the periphery of a core-print corresponding to the outer wall of the core to be inserted within the mold, the cylindrical portion A of the pattern being provided with radial cuts for their reception. The said wing portions C may furthermore consist of chills, which may be detachable from the remaining portion of the pattern, and may be left in the mold when the other part of the pattern is withdrawn; or they may consist of insulating material detachable from the pattern, and may be left in the mold when the rest of the pattern is withdrawn, and when the casting is formed they will occupy their positions as insulating material between the several radial sections of the commutator.

To provide for the uniting of the several sections of the casting when completed, and to further provide for a suitable flange around that end of the commutator toward the dynamo for the convenient attachment of the necessary wires, the pattern is provided with a flange E at one end extending outwardly from the body portion between the wings, and around the outside of the flange E, and, as herein shown, forming a part thereof, there is an annular ring portion *e*, which circumscribes the outer edges of the several wing-sections of the pattern. There is also formed beneath the outer edge of the opposite end of the portion A an annular ring *e'*, engaged with the body portion and forming a closure with the ends of the wings, and which may be divided beneath the lower ends of the several wing portions, so as to admit of the body portion of the pattern being withdrawn, leaving the wing portion C in position, if desired.

I have used the term "annular ring" to describe the part *e* for the reason that in the completed casting the ring corresponding to *e* in the pattern will be a continuous annular ring uniting the ends of the several radial sections of the commutator. I am aware that when the said ring is divided by openings beneath the ends of the several radial rings it becomes a divided or segmental ring or an an-

nular series of ring-sections as distinguished from a continuous annular ring. When the pattern is constructed so that the wings are drawn together with the other parts, the ring 5 e' will be a continuous annular ring and will be drawn with the other parts. In forming the mold, when the radial wings are intended to be left therein and the ring e' is for this purpose divided, the openings in the ring e' 10 below the ends of the radial wings will not be filled with sand, or at most only partially filled, leaving at all times a sufficient space in proximity to the ends of the radial wings to form a continuous annular ring in the casting. 15 When the cap-screws of ordinary construction have been applied to the opposite ends of the castings and the several radial sections have been thereby secured, the rings e and e' may be turned off, leaving the several radial sections 20 of the commutator separated by the insulating material. It will be observed that when it is desired to insert the insulating material after the several sections of the commutator are cast instead of before they are cast 25 the wings C act as chills and may be withdrawn, leaving spaces for the insulating material.

What I claim as my invention is—

1. The pattern for casting commutators, com-

prising a central body portion, wings extending longitudinally of and radiating from the central body portion, a flange extending outwardly from the body portion between the wings at one end, an annular ring forming a part of said flange in engagement with and 30 circumscribing the extreme outer edges of the radial wings at said end, and a ring forming, in connection with the ends of the several wings, a closure at the opposite end of the pattern, substantially as set forth. 35

2. The pattern for casting commutators, comprising the central body portion provided with wings radiating therefrom and detachable from the body portion, a flange extending outwardly from the body portion between the wings at one end of the pattern, a ring thereon surrounding the said flange and circumscribing the outer edges of the wings, and a segmental ring in contact with the ends of the wings at the opposite end of the pattern 40 45 to form a closure therewith, the segmental ring being divided at points beneath the several radiating wings, substantially as set forth. 50
